John L. Ray

UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

POWDER PUFF.

Application filed September 2, 1922. Serial No. 585,848.

To all whom it may concern:

Be it known that I, VICTOR GUINZBURG, a citizen of the United States, and a resident of the city, county, and State of New York, 5 have invented a certain new and useful Improvement in Powder Puffs, of which the following is a specification.

Heretofore powder puffs have been made with an outer covering of an absorbent textile material of pile fabric and internally 10 padded with some soft yielding material such as cotton or the like. This form of powder puff is of such absorbent material throughout that it absorbs moisture readily 15 and becomes damp and undesirable for use. Furthermore, if an attempt is made to wash it, the interior padding becomes compacted to such an extent as to render the puff flat, stiff and useless. Because of these undesirable 20 tendencies, a powder puff of the construction just mentioned soon becomes useless and is discarded.

The object therefore of this invention is to provide a powder puff of such construction 25 that the use of an absorbent lining or padding is avoided; which may be readily washed and will at all times retain a soft, yielding and desirable condition under all conditions of use.

30 This object is accomplished by the provision of means for retaining air within the puff which retains it in a soft, yielding and pliable condition.

For a more particular description of my 35 invention, reference is to be had to the accompanying drawing forming a part hereof, in which

40 Figure 1 is a cross-sectional view of a powder puff made in accordance with my invention.

Figure 2 is a plan view of the powder puff, parts being broken away to disclose construction.

45 Figure 3 is a view showing the powder puff as it appears when grasped by the hand ready for use.

Figure 4 is a plan view of the interior air casing; and

50 Figure 5 is a sectional view on the line 5—5 of Figure 4 looking in the direction of the arrows.

In the embodiment of my invention as disclosed in the accompanying drawing, I have shown the powder puff provided with

an outer covering of textile fabric, preferably a pile fabric such as velour or the like. The puff is generally made circular in outline and is shown constructed of two sections of material, 1 and 2 united together at their edges by seaming or stitching 3. This 60 forms a hollow casing, within which is disposed an inflated body or bag 4. This inflated bag is made of any material which possesses the ability to retain air indefinitely such as rubber or the like.

65 A form in which the bag may be made is disclosed in Figures 4 and 5 where it will be seen that the bag is of such form to smoothly fit the interior of the puff and is provided with a tubular extension or nipple 5 through 70 which the air may be forced to the interior of the bag and when a sufficient amount of air is placed therein, the end of the extension may be closed by vulcanizing or cementing or by any other suitable means.

75 It will be understood that just sufficient air is placed within the bag 4 to give sufficient softness or resiliency to the puff. One of the distinct advantages derived from this construction is that when the puff is grasped 80 by the hand, the air is shifted towards one edge of the puff providing a portion of rounded softness which contacts with the face.

85 As the bag 4 is made of impervious material and is not absorbent, the puff is not liable to become saturated with moisture. As it has no padding which can be damaged or compacted by washing, the puff can be washed and kept in a clean sanitary condition at all times.

90 From the foregoing it is obvious that my invention is not to be restricted to the exact embodiment shown but is broad enough to cover all structures coming within the 95 scope of the annexed claims.

What I claim is:

1. An article of the class described comprising a powder puff having means for retaining air within it.
2. An article of the class described comprising a powder puff having an outer fabric covering and air-retaining means within said covering.
3. An article of the class described comprising a powder puff having an outer covering and an air-filled body within the same.
4. An article of the class described com-

- prising a powder puff having an outer covering of pile fabric and an interior body of an impervious material filled with air.
5. An article of the class described comprising a powder puff having an outer covering and a rubber air-filled bag within the same.
6. An article of the class described comprising a powder puff having an outer pile fabric covering and pneumatic means within said covering for distending the same.
7. An article of the class described comprising a powder puff composed of an air inflated body covered by a pile fabric.
8. An article of the class described comprising a powder puff composed of a rubber bag inflated with air to such an extent as to provide a flat body of substantial thickness and a fabric covering for said body.

Signed at the city, county and State of
New York, this 29th day of August, 1922.

VICTOR GUINZBURG.
